UNITED STATES PATENT OFFICE.

MIKE MINTZ, OF ROCK ISLAND, ILLINOIS.

OILING DEVICE.

1,159,406.

Specification of Letters Patent.

Patented Nov. 9, 1915.

Application filed February 24, 1911. Serial No. 316,681.

To all whom it may concern:

Be it known that I, MIKE MINTZ, a citizen of the United States, residing at Rock Island, in the county of Rock Island and State of Illinois, have invented new and useful Improvements in Oiling Devices, of which the following is a full, clear, concise, and exact description, reference being had to the accompanying drawing, forming a part of this specification.

My invention relates to improvements in oiling devices for air compressor systems or the like and has for its object the production of means whereby the oil in suspension may be removed from the system and returned to its original receptacle.

A further object is the production of improved means for receiving and conducting said oil.

20 A further object is the production of a simple device that may be readily adapted for attachment to compressor systems, and one that is not liable to get out of order.

These, and such other objects as may hereinafter appear, are attained by my device, embodiments of which are illustrated in the accompanying drawings, in which—

Figure 1 represents a side elevation partly in section, showing my improved device in place; Fig. 2 represents a sectional view on the line 2—2 of Fig. 1, looking in the direction indicated by the arrows; Fig. 3 represents a sectional view on the line 3—3 of Fig. 2, looking in the direction of the arrows; Fig. 4 represents a reduced sectional view of a portion of Fig. 1, showing the diaphragm valve in section; Fig. 5 represents a sectional view on the line 5—5 of Fig. 4, looking in the direction of the arrows; Fig. 6 represents a perspective view of the oil receptacle.

Like numerals of reference indicate like parts in the several figures of the drawings.

Referring now to the drawings, my device comprehends a suitable motor 7 operating a pair of pumps, each comprising a cylinder 8, piston head 9, and a piston rod 10. An inwardly opening valve 11 communicates through a passage 12 with the interior of the cylinder back of the piston head. A second inwardly opening valve 13 is interposed between the passage 14 from the rear of the pump cylinder and the passage 15 leading to the diaphragm valve casing A. The diaphragm valve casing A comprises a lower

member 16 and an upper member 17 bolted or screwed together as shown at 18, and having a diaphragm 19 interposed between the upper and lower members, dividing the interior of the casing into a lower chamber A' and an upper chamber A". A pipe 20 connects the upper chamber with the suitable storage tank not shown. A tube 21 communicates with means (not shown) for actuating the automatic switch 22, by means of which the pressure of the air or gas within the tank and upper chamber A" regulates the action of the switch and automatically stops and starts the motor, as fully explained in a companion application filed on even date herewith.

The diaphragm 19 is provided with a centrally located valve 23, permitting the passage of air or gas from the pumps through the diaphragm to the storage tank, but preventing any return of the air or gas through the system. The air, as it passes upwardly, is forced through the passage 24 in the post 25 of the valve 23 and into the chamber A". In order to insure the best results, the interior of the pump cylinder must be kept thoroughly lubricated, and in order to do this, I have provided an oil cup 26 positioned below and at one side of the open end of each of the cylinders, within which a needle 27 secured to the piston head passes at each downward stroke of the piston, as fully explained in application Serial No. 467,040, heretofore filed by applicant. In this operation, the upper inner surface of the cylinder is kept constantly lubricated, and as the air or gas is forced through the system, it takes up a considerable portion of the oil which is consequently carried in suspension into the diaphragm valve chamber.

By reason of the fact that the diameter of the inlet passage 24 is greater than the diameter of the opening of the valve 23, the oil in suspension within the lower chamber A' collects on the under side of the diaphragm 19 and on the inner walls of the chamber and naturally gravitates to the bottom of the chamber, where, unless it is drawn off, it becomes thick and sticky. In order, therefore, to prevent this condition, I provide an oil release valve B, by means of which the oil may be periodically removed from the interior of the diaphragm valve chamber and returned to its original receptacle.

This oil release valve B consists in a

valve casing 28 having a screw threaded end 29, adapted to screw into an opening 30 in the base 31 of the diaphragm valve casing. A passage 32 connects the opening 30 with the interior of the chamber A' near its lower extremity, and the circumferential groove or depression 33 is provided connected with this opening so as to insure the withdrawal of all of the oil which collects within the diaphragm valve of the casing. Into the screw threaded end 29 of the valve casing 28 of the valve is screwed a small bushing 34 having an opening 35 communicating with the interior of the valve. A ball 36 is mounted within the opening 37 and held normally against the seat 38 by means of a spring 39. The opening 37 is contracted and extends into a large chamber 40 within the interior of the valve, and from this chamber a passage 41 extends directly out in line with the passage 37, and a second passage 42 extends downwardly therefrom through the nozzle 43.

The valve is controlled by means of a stem having an outer enlarged end 44, a large cylindrical portion 45 adapted to fit snugly within the passage 41, and a reduced end 46 adapted to rest against the ball 36. Communicating with the automatic switch 48 is bell crank lever 47, the upper arm 48 of which is operated by the switch, and the lower arm 49 of which is adapted to engage the outer end 44 of the valve stem.

The automatic switch operates at predetermined times to open the valve B, thus permitting the oil that has gathered in the bottom of the chamber to escape therefrom. As clearly explained in a companion application, this operation of the bell crank lever 48 takes place when the current is shut off and the motor stopped, the valve remaining open until the motor again starts. Hence, while the motor is in operation, the air is being forced through the diaphragm into the compressed air tank. As soon, however, as the motor is shut off, the oil release valve is automatically opened, the valve 33 is closed, and the compressed air within the chamber A' escapes through the valve B, carrying with it the oil in suspension, forcing before it any oil that may have accumulated in the bottom of the chamber and in the opening 30 and passage 32. This operation tends to keep the system at all times clear of any oil and keeps the entire system clean.

In order to utilize the oil that passes out through the oil release valve, I provide an oil receptacle D, comprising an enlarged flattened tube 50, having a portion of its ends opened as shown at 51, but with the lower half of the ends closed by a plate 52. This receptacle is also provided near its extreme ends with a pair of tubes 53-53', extending downwardly and opening into the oil cups 26 at 54. This receptacle is mount-

ed on the motor casing in any suitable manner as by means of bands 55 surrounding the tubes, and the enlarged tube is positioned directly below the valve nozzle 43, the passage 42 of which opens directly into the tube 50 as shown in Fig. 3. The bottom of the tube 50 is also slightly bent upwardly at the center, as shown at 56, consequently its ends are below the level of the center. This insures accurate distribution of the oil between the two tubes 53-53' and consequently provides that an equal amount of oil shall be supplied to the two oil cups 26. The provision of the end plates 52 prevents any possible escape of the oil by reason of the high pressure within the diaphragm chamber blowing the oil too hard against the bottom of the tube, while the upper open portion permits the escape of the air or gas after it is relieved of its oil in suspension.

The complete closing of the ends of the tube would ordinarily give the compressed air sufficient chance to expand with the result that the oil would be blown out of the cups. This tendency to blow the oil out is also overcome by making the opening 35 leading into the valve of less diameter than the opening 42 leading from the nozzle, thus permitting expansion of the oil laden air or gas before it is forced into the tube.

In order to insure the more perfect separation of the oil in suspension, I provided a pair of baffle plates 57, one near each end of the interior of the tube and extending down over the top below the plates to the level of the end plates 52, this preventing the escape of oil without limiting the direct expansion of the compressed air. By the use of this device, it will be noted that in addition to keeping the system properly lubricated and cleaned, I also provide means for saving nearly all of the oil used, which is periodically returned to its original receptacle and from it used over, making it necessary to replenish the oil cups at long intervals of time. While I have shown specific means by which this result is obtained, it is evident that I do not limit myself to such specific construction, as other forms may be used without departing from the spirit of my invention.

I claim:

1. In a device of the class described, the combination with a compressed air chamber, a release valve opening therefrom, a receptacle having its ends partially open, and tubes leading from the extremities of said receptacle to the original oil receptacle.

2. In a device of the class described, the combination with a compressed air chamber, a release valve opening therefrom, a receptacle having the upper portion of its ends partially open; and tubes leading from the extremities of said receptacle to the original oil receptacle.

3. In a device of the class described, the combination with a compressed air chamber, a release valve opening therefrom, a receptacle elevated at the center having its ends partially open, and tubes leading from the extremities of said receptacle to the original oil receptacle.

4. In a device of the class described, the combination with a compressed air chamber, a release valve opening therefrom, a receptacle elevated at the center having the upper portion of its ends partially open, and tubes leading from the extremities of said receptacle to the original oil receptacle.

5. In an air compressor, the combination with a motor, pumps, a compressed air tank, a diaphragm valve interposed between said pumps and tank, means for reducing the pressure in the system between the pumps and diaphragm valve to atmospheric regardless of the pressure in the remainder of the system, and means for recovering the oil in suspension simultaneously with the reduction in pressure.

6. In an air compressor, the combination with a motor, pumps, a compressed air tank, a diaphragm valve interposed between said pumps and tank, means for reducing the pressure in the system between the pumps and diaphragm valve to atmospheric regardless of the pressure in the remainder of the system, means for recovering the oil in suspension simultaneously with the reduction in pressure, said means comprising a valve, means for opening said valve at predetermined times so that the pressure of air within said system will force the oil laden air through said valve, and means for collecting said oil.

7. In an air compressor, the combination with a motor, pumps, a compressed air tank, a diaphragm valve casing interposed between said pumps and tank, a diaphragm valve dividing said casing into an upper and lower chamber, means for reducing the pressure in the system between the pumps and diaphragm valve to atmospheric regardless of the pressure in the remainder of the system, and means for recovering the oil in suspension simultaneously with the reduction in pressure.

8. In an air compressor, the combination with a motor, pumps, a compressed air tank, a diaphragm valve casing interposed between said pumps and tank, a diaphragm valve dividing said casing into an upper and lower chamber, means for reducing the pressure in the system between the pumps and diaphragm valve to atmospheric regardless of the pressure in the remainder of the system, means for recovering the oil in suspension simultaneously with the reduction in pressure, said means comprising a valve means for opening said valve at predetermined times so that the pressure of air

written said system will force the oil laden air through said valve, and means for collecting said oil.

9. In an air compressor, the combination with a motor, a compressed air tank, a diaphragm valve casing interposed between said pumps and tank comprising a diaphragm provided with a valve and dividing the interior of said casing into an upper and lower chamber, a release valve for reducing the pressure in the system between the pumps and diaphragm valve to atmospheric regardless of the pressure in the remainder of the system, means for recovering the oil in suspension within the system simultaneously with the reduction in pressure, said means comprising a receptacle having its ends partly open, and tubes leading from the extremities of said receptacle to the original oil receptacle.

10. In an air compressor, the combination with a motor, a compressed air tank, a diaphragm valve casing interposed between said pumps and tank comprising a diaphragm provided with a valve and dividing the interior of said casing into an upper and lower chamber, a release valve for reducing the pressure in the system between the pumps and diaphragm valve to atmospheric regardless of the pressure in the remainder of the system, means for recovering the oil in suspension within the system simultaneously with the reduction in pressure, said means comprising a receptacle having the upper portion of its ends partly open, and tubes leading from the extremities of said receptacle to the original oil receptacle.

11. In an air compressor, the combination with a motor, a compressed air tank, a diaphragm valve casing interposed between said pumps and tank comprising a diaphragm provided with a valve and dividing the interior of said casing into an upper and lower chamber, a release valve for reducing the pressure in the system between the pumps and diaphragm valve to atmospheric regardless of the pressure in the remainder of the system, means for recovering the oil in suspension within the system simultaneously with the reduction in pressure, said means comprising a receptacle elevated at the center and having its ends partly open, and tubes leading from the extremities of said receptacle to the original oil receptacle.

12. In an air compressor, the combination with a motor, a compressed air tank, a diaphragm valve casing interposed between said pumps and tank comprising a diaphragm provided with a valve and dividing the interior of said casing into an upper and lower chamber, a release valve for reducing the pressure in the system between the pumps and diaphragm valve to atmospheric regardless of the pressure in the remainder of the system, means for recovering the oil in suspension within the system simultaneously with the reduction in pressure, said means comprising a valve means for opening said valve at predetermined times so that the pressure of air

of the system, means for recovering the oil in suspension within the system simultaneously with the reduction in pressure, said means comprising a receptacle elevated at the center and having the upper portion of its ends partly open, and tubes leading from the extremities of said receptacle to the original oil receptacle.

13. In an air compressor system, pumps, a storage reservoir, a valve interposed therebetween, means for relieving the pressure below said valve and automatic devices for removing the oil in suspension from the compressed air, including a chamber partially open at both ends.

14. In an air compressor system, pumps, a storage reservoir, a valve interposed therebetween, and means for moving the oil in suspension from the compressed air, said means comprising a tube, having the lower

portion of its ends partly closed and having baffle plates extending downwardly from within said tube near said open ends.

15. In an air compressor system, an air pump, oiling means, a storage reservoir, an air chamber and a valve therefor interposed between the pump and the reservoir, a device for exhausting the air from said chamber when said valve is closed, and means for separating the oil from the air during the exhausting action, said means including a chamber partially open at both ends.

In witness whereof, I have hereunto subscribed my name in the presence of two witnesses.

MIKE MINTZ.
